IGNITION AND CONTROL DEVICE FOR OVEN
BURNERSBirchard L. Matthews, Cleveland, Ohio, assignor
to The Patrol Valve Company, Cleveland, Ohio,
a corporation of Ohio

Application October 20, 1931, Serial No. 569,968

5 Claims. (Cl. 158—117.1)

This invention relates to ignition and control devices and in particular devices of the type disclosed for effecting the ignition and control of an inclosed gas burner by means of a remote pilot 5 burner and a thermostatic valve.

One of the objects of this invention is to provide an improved safety ignition device for an inclosed burner in which the ignition of such burner is effected by means of a continuously operating 10 pilot burner which is located at a point remote from the burner and its housing.

A further object of this invention is to provide a control device for inclosed gas burners which is arranged to provide an ignition means for such 15 burner before its gas supply can be turned on.

With these and other objects in view, the invention consists in the novel construction, arrangement and combination of parts, hereinafter described, illustrated in some of its embodiments 20 in the accompanying drawings and particularly pointed out in the appended claims.

In the drawings, Figure 1 is a plan view of a gas range illustrating one mode of practicing my invention; Figure 2 is an enlarged side elevational view, partly in section, showing my improved oven burner control. Figure 3 is a sectional view taken on line 3—3, Figure 1, and Figure 4 is a sectional view taken on the axis of one of the needle adjusted valves.

Referring to Figure 1, the numeral 1 indicates generally a conventional gas range having a plurality of top burners 2, and an inclosed oven 3 which is arranged to be heated by means of the oven burner 4. The range is supplied with gas by means of a gas supply conduit 5 which communicates with the range manifold 6 from which a plurality of valves 7 control the gas supply of the top burners 2. A similar valve 8 is connected to the manifold 6 for controlling the gas supply 25 of the oven burner 4. The range is provided with a flash tube igniter 9 having a continuously operating pilot burner 10. The flash tubes 11 are open at each end for the purpose of conducting gas from the burners 2 to the continuously operating pilot burner 10.

The conduction of gas from the burners 2 to the pilot burner 10 may be effected by any of the usual methods such as an injection port drilled in the side of each of the burners adjacent the 30 open end of the associated flash tube which is supported by such a burner. Thus, when gas is supplied to any of the burners 2, a certain portion of it is injected into a flash tube which conducts it to the flame of the pilot burner 10 35 effecting the ignition of the gas in the flash tube,

which flashes back and effects the ignition of the gas supplying main burner.

The fuel supply of the pilot burner 10 is by way of the conduit 12 which is under control of a valve 13 and the needle adjusted gas and air mixing valve 55. The gas supply of the oven burner 4 is under the joint control of the manually operable valve 8, a thermostatically operated oven regulator 14 and a thermally actuated valve 15. The oven burner is arranged to be lighted 10 by an ignition burner 16.

The control of the oven burner 4 is primarily effected by the manually operable valve 8 which communicates with the gas supply manifold 6 as shown. Upon the opening of the valve 8, gas is 15 supplied to the conduit 17 which communicates with the inlet side of the thermally actuated valve 15. This valve is normally in a closed position. The valve 15 includes a valve body 18 having a valve seat 19 integrally formed therewith. A second valve seat 20 is provided by a closure cap 21 which is carried in an opening formed in the side of the valve body. A valve head 22 operates between the valve seats 19 and 20 to control the flow of fuel therethrough. 20

The valve head 22 is secured to a valve stem 23 operatively associated with a snap-action mechanism 24 which is in turn connected by means of an adjustable rod 25 to a bimetallic thermostatic bar or strip 26. The thermostatic 30 bar 26 is fixedly secured by a bolt and nut 27 to the housing 28. An auxiliary gas burner 29 is provided for supplying heat to the thermostat 26 for the actuation of the valve 15. The burner 29 is supplied with gas by way of the valve port 35 20, a conduit 30 and the needle adjusted gas and air mixing valve 31 which provides the burner 29 with a combustible mixture of gas and air so that this burner operates with a blue flame.

The valve body 18 is provided on its inlet side 40 with an opening in which there is received a fitting 32 which is in communication with the conduit 33. This conduit communicates with the needle adjusted gas and air mixing valve 34, which is arranged to supply a combustible mixture of gas and air to the ignition burner 16 and its ignition tube injector 35. 45

The gas and air needle adjusted mixing valves 31, 55 and 34 are of similar construction and one of them is shown in detail in Figure 4. This 50 valve includes a body portion 36 having a port 37 with which an adjustable needle 38 cooperates for controlling the flow of gas therethrough. The end of the valve body is provided with a closure cap 39. Air inlet openings 40 are provided above 55

the gas injection port 37 for the purpose of supplying air to the gas stream flowing through the valve. An adjustable cap 41 is provided for regulating the air supplied by way of the openings 40. 5 The injector nozzle 35 is positioned directly below a chimney 42 which is slotted at 43 for reception of the set screw 44 so that its position may be adjusted with respect to the injector nozzle 35. The chimney 42 is cut away at its lower end as 10 illustrated in Figure 3 of the drawings so that the injector nozzle 35 and the adjacent port of the burner 16 are ignitable one from the other. An L-shaped flash tube 45 is slidably received in the upper end of the chimney 42 and rests on a collar 15 46 rigid with the chimney. An air inlet port 47 is provided in the under side at the bend of the L-shaped flash tube 45. The flash tube 45 terminates at a point adjacent the flame of the pilot burner 10 so that gas is conducted by this tube 20 to the pilot and is ignitable thereby.

The ignition burner 16 is provided with a plurality of ports 48 which extend from a point adjacent to the injector nozzle 35, to the oven burner 4 which is in turn provided with flame supporting ports 49. The outlet side of the thermally actuated valve 15 communicates with a conduit 50 which is connected to the inlet side of the thermostatically controlled oven regulator valve 14. The outlet side of the thermostatic valve 14 communicates with a conduit 51 which supplies gas to the gas and air mixing tube 52 of the oven burner 4. The valves 7, 8, 13 and 14 do not form a part of this invention and they are not described in detail as they represent any valve suitable for the 35 purpose employed. The valve 15, considered by itself is disclaimed apart from this invention and it forms in part the subject matter of application for United States Letters Patent, Serial No. 271,805, filed by Edmund J. TePas, April 21, 1928, 40 which has resulted in Patent No. 1,842,334 issued January 19, 1932.

When it is desired to operate the oven burner, the valve 8 is opened whereupon a supply of gas is admitted to the conduit 17. Under such conditions, the valve 15 normally would be occupying the position shown in Figure 2, wherein the valve head 22 is shown in contact with the seat 19, while the valve seat 20 is uncovered. With the parts in the position just described, the gas supplied by way of the conduit 17 passes through the port defined by the uncovered valve seat 20, and thence to the conduit 30 and the mixing valve 31, which supplies a combustible mixture of gas and air to the auxiliary burner 29. While the above 55 operation is taking place, the conduit 33 is supplied with gas which is carried to the mixing valve 34 which supplies a combustible mixture of gas and air to the injector nozzle 35 and the associated ignition burner 16.

From the foregoing, it is apparent that when the manually operable oven control valve 8 is turned on, gas is supplied to the burners 16, 29 and the nozzle 35 substantially simultaneously. Almost immediately upon the supplying of gas to these burners, the gas supplied to the nozzle 35 is conducted by the chimney 42 and its associated flash tube to the continuously operating pilot burner 10, whose flame serves to ignite the combustible mixture emitted from the open end of this tube which is adjacent the flame of this pilot burner, whereupon a flash is produced in the tube which causes the ignition of the gas escaping from the nozzle 35 and the burners 29 and 16.

In a short time, the flame of the auxiliary burner 29 has heated the thermostat 26 suffi-

ciently to cause its lower free end to shift to the left as viewed in Figure 2 effecting the opening of the valve 15 whereupon a supply of gas is admitted to the oven burner 4 by way of the conduits 50 and 51 and the oven regulator valve 14. 5

The gas admitted to the oven burner 4 is then ignited by the flame supported by the ignition burner 16. The device then operates under control of the thermostatic valve 14 which is provided with a manually settable handle 54 by 10 means of which a predetermined temperature may be maintained in the oven. The ignition burner 16 is supplied with gas at full line pressure at all times and its operation is not affected by the valve 14 which automatically controls the 15 flow of gas to the oven burner, and as sometimes happens, this valve may cut down the flow of gas to the oven burner to such a point so that a slight draft or disturbance in the oven will cause its extinguishment.

Extinguishment of the oven burner under these conditions would cause no harm as it would be re-ignited immediately by the ignition burner 16 as this burner is operating at full capacity and hence is not so easily extinguished as is the 25 oven burner under the conditions just outlined.

Upon the uncovering of the valve seat 19, the valve head 22 is shifted into engagement with the valve seat 20, temporarily cutting off the supply of gas to the auxiliary burner 29. After this 30 operation takes place, the thermostat 26 cools and its lower free end starts to move to the right as viewed in Figure 2, whereupon the spring 53 causes the valve head to follow the movement of the thermostat 26 and the associated rod 25 35 and snap-action mechanism 24, whereupon a supply of gas is again provided for the burner 29.

In this manner, when the valve 8 is open the gas supply of the burner 29 is regulated so as to provide an amount of heat just sufficient to 40 maintain the valve head 22 in open valve position with respect to its seat 20.

From the foregoing, it is apparent that I have provided a safety control and ignition means for an inclosed burner in which the ignition of the 45 burner is effected by means of a remote pilot and an associated ignition burner having a portion adjacent the inclosed burner. The ignition burner by reason of being supplied at all times with a gas supply at full line pressure, is not apt to be readily extinguished as is the burner which it serves to ignite, such burner being under control of a thermostatic valve which increases and decreases its gas supply causing it to burn at times with a small flame which is apt to be easily extinguished.

The provision of the thermally actuated valve 15 invests the appliance with a high degree of safety as the use of this valve necessitates the presence of an ignition flame for the oven burner before it can be supplied with gas. The use of an ignition burner 16 spanning part of the distance between the oven burner and the pilot light provides a positive and safe means for igniting the oven burner and at the same time permits the locating of the thermally actuated valve exteriorly of the oven where it is not affected by the heat of the oven burner.

Furthermore, it is to be understood that the 70 particular forms of apparatus shown and described, and the particular procedure set forth, are presented for purposes of explanation and illustration and that various modifications of said apparatus and procedure can be made without 75

departing from my invention as defined in the appended claims.

Having thus described my invention, what I claim is:

5 1. In a gas burner control and ignition device, in combination, a main heating burner, a remotely positioned continuously operating pilot burner located outside the range of normal lighting proximity with respect to said main burner, an ignition burner located in lighting proximity to said main burner, an injection nozzle provided by said ignition burner, and a flash tube having a vertically disposed portion adjustably secured to said ignition burner in gas conducting relation 10 15 above said nozzle for conveying gas to said pilot burner and effecting the ignition of said ignition burner.

2. A device of the kind described, a main burner, a constant pilot remote therefrom, an ignition burner for said main burner and remote from said constant pilot, an auxiliary burner in ignitable relation with the ignition burner, said burners being connected with a source of fuel, means dependent upon ignition of the auxiliary 25 burner for causing the flow of and maintaining the flow of fuel to the main burner and for decreasing the flow of fuel to the auxiliary burner, a valve for controlling the flow of fuel to the ignition and auxiliary burners and means to 30 transmit flame from the constant pilot to the ignition burner.

3. A device of the character described comprising a main burner, a fuel line therefor, a valve in the fuel line, temperature responsive means for controlling the valve, an auxiliary burner controlling the temperature responsive means of said valve, a pilot disposed remotely from said main burner, an elongated ignition burner in ignitable relation with said main burner, a valve in the fuel line for causing fuel to be supplied to the first mentioned valve and to said ignition burner, and means for conducting fuel

from said ignition burner to said pilot whereby to light said ignition burner upon opening of said second valve, and said auxiliary burner being located adjacent to and ignitable from said ignition burner.

4. A device of the character described comprising a casing, a main burner within said casing, a fuel line therefor, a valve in the fuel line, temperature responsive means for controlling the valve, an auxiliary burner controlling the temperature responsive means, a constant pilot, an elongated ignition burner extending through said casing and in ignitable relation with said main burner, a valve in the fuel line for causing fuel to be supplied to the first valve and to said ignition burner, said valves, temperature responsive means, and a portion of said ignition burner being disposed outside said casing, and means for conducting fuel from the external portion of said ignition burner to said pilot whereby to light said ignition burner upon opening of said second valve, and said auxiliary burner being located adjacent to and ignitable from said ignition burner.

5. A device of the kind described comprising a main burner, a fuel line therefor, a valve in the fuel line, thermal means responsive to an increase in temperature to open said valve, an auxiliary burner effecting the operation of said thermal means, an ignition burner adapted to ignite said main and auxiliary burners, a constant pilot disposed remotely from the main burner, a fuel duct from the ignition burner connected with the fuel line ahead of said valve, means conveying fuel from the ignition burner to said pilot whereby to ignite said ignition burner, a fuel duct from said valve to said auxiliary burner, and means controlling the supply of fuel through said last duct dependent upon the opening and closing of said valve.

BIRCHARD L. MATTHEWS.
